UNITED STATES PATENT OFFICE.

CARL G. SWENSON, OF INDIANAPOLIS, INDIANA, ASSIGNOR TO THE OAKES COMPANY, OF INDIANAPOLIS, INDIANA, A CORPORATION OF INDIANA.

PROCESS OF MAKING BALL-BEARING CONES.

1,228,352.

Specification of Letters Patent.

Patented May 29, 1917.

Application filed July 7, 1916. Serial No. 108,041.

To all whom it may concern:

Be it known that I, CARL G. SWENSON, a citizen of the United States, residing at Indianapolis, in the county of Marion and 5 State of Indiana, have invented a new and useful Process of Making Ball-Bearing Cones, of which the following is a specification.

It is the object of my invention to produce a pressed steel ball-bearing cone from sheet metal.

The accompanying drawing illustrates the various steps of my invention, the apparatus used for carrying it out, and also the initial 15 disk of sheet metal and the final product—a pressed steel ball-bearing cone. In the drawing, Figure 1 is a section through the first set of dies, for performing the first two punching operations, with the double-acting 20 punch raised; Fig. 2 is a similar view through the same set of dies, with the punch lowered and the second step of the operation completed; Fig. 3 is a similar section through the second pair of dies for performing the third punching operation, with the punch raised after completing its operation; Fig. 4 is a similar section through the third set of dies, for performing the fourth 25 punching operation; Fig. 5 is a similar section through the fourth set of dies, for performing the fifth punching operation; Fig. 6 is a similar section through the fifth set of dies, for performing the last punching operation; Fig. 7 is a perspective view of 30 the sheet metal disk produced by the first step of the operation, as the starting point for the process; and Fig. 8 is a perspective view of the finished ball-bearing cone produced by my process from the sheet metal 40 disk shown in Fig. 7.

The sheet metal plate 10 of suitable thickness is first placed on the lower die 11 of the first set of dies, beneath a double-acting punch having an outer part 12 and 45 an inner part 13, and then the double-acting punch is caused to descend so that the outer part 12 first co-operates with the lower die 11 to stamp out from the sheet metal plate 10 a blank in the form of a sheet metal disk 14, as shown in Fig. 1. This 50 disk is shown in perspective in Fig. 7. As soon as the outer part 12 of the double-acting punch has stamped out the disk 14, the

inner part 13 descends through the outer part 12 and presses the disk 14 through the 55 contracting opening in the die 11 to produce from such disk a cup 15 the side walls of which are composed of elements all substantially parallel to the cup axis, as shown in Fig. 2, this cup when formed dropping 60 from the die 11 into a receptacle below. The two steps illustrated in Figs. 1 and 2 may be separated, but are preferably parts of one continuous operation, as illustrated.

Then the cup 15 is placed closed end 65 downward on the lower die 20 of the second set of dies, and the co-operating punch 21 descends upon it to force it into the die 20 to produce the bell 22, as shown in Fig. 3. To do this the punch 21 is smaller than the 70 upper end of the die 20, so that it can pass into it freely, and the opening in such die is contracted downward so as to compress the cup 15 into the bell 22 of smaller diameter, thereby thickening the walls to provide 75 material for the ball race, the body of the cone, and the polygonal flange to be formed afterward. In order to obtain this compression effectively, it is essential that the cup 15 be substantially parallel-sided, 80 so that when the punch 21 acts axially on it in the die 20 the pressure will be in line with the parallel elements of the side walls thereof, so that the contracting opening in the die 22 may act radially on such walls to 85 force them inward and thicken them at the desired points. When the bell 22 has been formed, the punch 21 is raised and the bell forced upward out of the die 20. The bell 22 when formed has a bell-shaped 90 exterior and a substantially straight-sided interior surface, as illustrated in Fig. 3.

When the bell 22 has been formed and removed from the die 20, it is placed closed end downward in the die 25 of the third 59 set of dies, fitting in such die, and a punch 26 is caused to descend through the upwardly spring-pressed stripper plate 27 into the open end of such bell to punch a hole through its closed end, thereby producing 100 the perforated bell 28 illustrated in Fig. 4. When the punch 26 rises out of the die 25 it carries the perforated bell with it, and such bell is stripped off such punch by the stripper plate 27. Conveniently, the die 25 105 and the punch 26 are tilted from the vertical,

so that when the perforated bell 28 has been stripped from the punch 26 by the stripper plate 27 it will not fall back into the hole in the die 25 but will slide off the upper surface of such die into a receptacle placed to receive it; however, this is a detail which is a mere convenience, so that it is not illustrated.

5 The portion which is stamped out of the crown or closed end of the bell 22 in producing the perforated bell 28 falls through the die 25.

The perforated bell 28 after being stripped from the punch 26 is placed on the lower die 30 of the fourth set of dies. This die 30 has a convex portion 31 for forming the ball race in the finished cone. A punch 32 is caused to descend upon the die 30 to cause the perforated bell 28 to be forced into the hole in such die and the material at the flaring end of the bell to be spread out into a flat portion 33, which is to form the polygonal flange on the finished cone. The punch 32 has a central projection 34 which extends into the hole in the flaring end of the bell, and within the die 30 there is a movable member 35 which normally forms the bottom of such die and has a central upwardly projecting portion 36 extending into the hole at what was originally the closed end of the bell, so as to force outward against the die portion 31 the material at such end and thus produce a compression of the metal at the ball race which is formed at such portion 31. By this compression, following the previous operations, the grain of the metal at the ball race formed by the portion 31 is materially changed from its original character, the grain being made finer and the material harder as a result, so that the ball race may 40 the better resist wear. When by reason of the descent of the punch 32 the perforated bell 28 has been pressed into the shape shown in Fig. 5 to form the rough flanged cone 37, such punch is raised, and then the rough flanged cone is forced upward out of the die 30 by causing the movable member 35 to move upward.

The rough flanged cone is now placed on the lower die 40 of the fifth and last set of dies, which die 40 has a polygonal opening through it, and a polygonal punch 41 is caused to descend upon it to cut off the surplus of the rough flange 33 to produce the finished polygonal or other non-circular flange 42.

55 The cone with the finished flange is now placed in a tapping machine reamed and tapped to produce an internal thread 43. The finished ball-bearing cone 44 thus produced is shown in Fig. 8.

In carrying out my process, I find it desirable to anneal the article at one or two intermediate stages of the process; preferably first after the cup 15 has been formed and again after the perforated bell 28 has

been formed, and when the finished ball-bearing cone has been produced I preferably case-harden it.

I claim as my invention:

1. The process of making pressed steel ball-bearing cones, comprising stamping out a sheet metal disk, pressing the disk through a die to form a cup the side walls of which have substantially parallel elements, annealing the cup, forcing the cup into a contracting die by pressure in alignment with the parallel elements of the side walls of the cup to compress the cup into a member which is bell-shaped exteriorly and substantially straight-sided interiorly, punching a hole through the closed end of this bell, annealing the perforated bell, forcing the perforated bell into a die which has a convex portion to form a ball race and an interior portion which acts on the recently perforated end of the bell to force the adjacent metal out into the ball race, spreading out the flaring end of the perforated bell to form a plane flange, punching out this flange into the desired non-circular shape, and screw-threading internally the ball-bearing cone thus produced.

2. The process of making pressed steel ball-bearing cones, comprising stamping out a sheet metal disk, pressing the disk through a die to form a cup the side walls of which have substantially parallel elements, forcing the cup into a contracting die by pressure in alignment with the parallel elements of the side walls of the cup to compress the cup into a member which is bell-shaped exteriorly, punching a hole through the closed end of this bell, forcing the perforated bell into a die which has a convex portion to form a ball race, spreading out the flaring end of the perforated bell to form a plane flange, punching out this flange into the desired non-circular shape, and screw-threading internally the ball-bearing cone thus produced.

3. The process of making pressed steel ball-bearing cones, comprising stamping out a sheet metal disk, pressing the disk through a die to form a cup the side walls of which have substantially parallel elements, annealing the cup, forcing the cup into a contracting die by pressure in alignment with the parallel elements of the side walls of the cup to compress the cup into a member which is bell-shaped exteriorly, punching a hole through the closed end of this bell, annealing the perforated bell, forcing the perforated bell into a die which has a convex portion to form a ball race, spreading out the flaring end of the perforated bell to form a plane flange, punching out this flange into the desired non-circular shape, and screw-threading internally the ball-bearing cone thus produced.

4. The process of making pressed steel

- ball-bearing cones, comprising stamping out a sheet metal disk, pressing the disk through a die to form a cup the side walls of which have substantially parallel elements, forcing the cup into a contracting die by pressure in alinement with the parallel elements of the side walls of the cup to compress the cup into a member which is bell-shaped exteriorly and substantially straight-sided in 10 teriorly, punching a hole through the closed end of this bell, forcing the perforated bell into a die which has a convex portion to form a ball race, spreading out the flaring end of the perforated bell to form a plane flange, punching out this flange into the desired non-circular shape, and screw-threading internally the ball-bearing cone thus produced.
5. The process of making pressed steel ball-bearing cones, comprising stamping out a sheet metal disk, pressing the disk through a die to form a cup the side walls of which have substantially parallel elements, forcing the cup into a contracting die by pressure in alinement with the parallel elements of the side walls of the cup to compress the cup into a member which is bell-shaped exteriorly, punching a hole through the closed end of this bell, forcing the perforated bell into a die which has a convex portion to form a ball race, and having an interior portion which acts on the recently perforated end of the bell to force the adjacent metal out into the ball race, spreading out the flaring end of the perforated bell to form a plane flange, punching out this flange into the desired non-circular shape, and screw-threading internally the ball-bearing cone thus produced.
- 0 6. The process of making pressed steel ball-bearing cones, comprising stamping out a sheet metal disk, pressing the disk through a die to form a cup the side walls of which have substantially parallel elements, forcing the cup into a contracting die by pressure in alinement with the sides of the cup to compress the cup into a member which is bell-shaped exteriorly, punching a hole through the closed end of this bell, forcing the perforated bell into a die which has a

convex portion to form a ball race, and spreading out the flaring end of the perforated bell to form a plane flange.

7. The process of making pressed steel ball-bearing cones, comprising stamping out a sheet metal blank, pressing it into the form of a cup the side walls of which have elements all substantially parallel to the cup axis, compressing the cup by co-acting axial and radial forces to thicken the walls and produce a bell-shaped member, perforating such bell-shaped member at its crown, compressing this perforated end of the bell-shaped member by co-acting axial, outward, and inward forces and forming an external ball race therein, and forcing back into a plane the flaring end of the bell.

8. The process of making pressed steel articles, comprising stamping out a sheet metal disk, pressing the disk through a die to form a cup the side walls of which have substantially parallel elements, and compressing this cup in a die by a punch with the parallel elements of the side walls of the cup in alinement with the direction of pressure of the punch.

9. The process of making pressed steel articles, comprising stamping out a sheet metal disk, pressing the disk into the form of a cup the side walls of which have substantially parallel elements, and compressing this cup in a die by a punch acting in alinement with the parallel elements of the side walls of said cup to thicken such side walls and force the metal of the cup outward.

10. The process of making pressed steel articles, comprising stamping out a sheet metal disk, pressing the disk through a die to form a cup the side walls of which have substantially parallel elements, compressing this cup in a die by a punch with the parallel elements of the side walls of the cup in alinement with the direction of pressure of the punch, forming a hole through this member, and screw-threading such hole.

In witness whereof, I have hereunto set my hand at Indianapolis, Indiana, this 19th day of June, A. D. one thousand nine hundred and sixteen.

CARL G. SWENSON.
